UNITED STATES PATENT OFFICE.

THOMAS D. WRIGHT, OF SPRINGVILLE, ALABAMA.

CONCRETE TIE.

1,381,048.

Specification of Letters Patent.

Patented June 7, 1921.

Application filed July 29, 1920. Serial No. 399,942.

To all whom it may concern:

Be it known that I, THOMAS D. WRIGHT, a citizen of the United States of America, residing at Springville, in the county of 5 Saint Clair and State of Alabama, have invented new and useful Improvements in Concrete Ties, of which the following is a specification.

The object of the invention is to provide 10 a railroad tie of a construction which will provide a proper support for the rails, as a substitute for the wooden ties now ordinarily employed and which will have the improved means for securing the rails in their proper 15 relation while permitting a sufficient cushioning of the same to avoid the objections ordinarily urged against concrete and metallic ties as heretofore constructed, and with this object in view the invention consists in 20 the construction and combination of parts of which a preferred embodiment is shown in the drawings wherein:

Figure 1 is a perspective view of a tie embodying the invention and showing at one 25 end thereof a portion of a rail secured in operative position.

Fig. 2 is a plan view of the tie.

Fig. 3 is a bottom plan view of the same, the filler being omitted.

30 Fig. 4 is a longitudinal sectional view on the plane indicated on the line 4—4 of Fig. 1 with the filler omitted.

Fig. 5 is a transverse section on the plane indicated by the line 5—5 of Fig. 1.

35 Fig. 6 is a detailed view of one of the rail clamping jaws.

The tie embodies essentially a shell or box 10, preferably of metal, open at its upper and lower sides, the lower side thereof being 40 spanned transversely by the brace bars 11, flush with the lower edges of the side walls of the shell, and the upper side thereof being spanned by transverse seat bars 12 which are arranged respectively in the planes of 45 the railroad rails 13, indicated in Figs. 1 and 4, or at an interval corresponding with the proposed distance between the rails which are to be seated upon the tie.

The rest bars 12 are preferably depressed 50 slightly below the upper edges of the side walls of the shell, as indicated clearly in Fig. 5, so that the base or foot 14 of the rail 13 is spaced slightly above the surface of the corresponding rest bar and a minute dis-

tance also above the upper edges of the side walls.

Arranged in operative relation with each rest bar is a rail clamp consisting of co-operating jaws 15 adapted to extend over and engage the foot of the rail, as shown in 60 Fig. 4, the shank portions 16 of said jaws being fulcrumed by means of pins 17 which are fitted in vertical slots 18 formed in longitudinal reinforcing bars 19 preferably extending from end to end of the shell and terminally secured to the end walls thereof by means of rivets 20, as indicated in Fig. 3. The members or jaws of the clamp are adjustably connected by means of a bolt 21 extending through registering openings in said 70 jaws and fitted with a nut 22, said bolt extending between the rest bar 12 and the undersurface of the rail foot midway between and parallel with the upper edges of the side walls of the tie shell to the end that 75 there is a possibility of a slight yielding movement of the rail sufficient to cushion any shock or jar applied thereto, such yielding movement being communicated from the rail foot through the adjusting rod or bolt 80 21 to the rest bar 12, and the jaws being adapted for corresponding yielding movement by reason of the engagement of the fulcrum pins 17 with the slots 18 in the lower edges of the longitudinal bracing members 85 19.

The interior of the shell is occupied by a filler 23 of concrete or cement which, however, is omitted adjacent to the jaws of the clamping members, as indicated at 24, to 90 permit of the manipulation of the jaws to either clamp or release the rails, it being obvious that by the arrangement of the adjusting rods or bolts 21 near the planes of the upper edges of the side walls of the 95 shell, the fastening or unfastening of the rails may be effected without displacing a tie or disarranging the elements thereof.

Having described the invention, I claim:

1. A rail tie consisting of a metallic shell 100 having parallel side walls and provided with a filler of concrete, longitudinal reinforcing bars arranged in parallel relation with the side walls of the shell, transverse bottom braces connecting the side walls beneath 105 the lower edges of said reinforcing bars, transverse rest bars disposed adjacent to the upper edge of the shell in the planes of the

rails supported by the tie, and clamping means for securing the rails in position, and consisting of relatively movable jaws pivotally mounted upon said longitudinal reinforcing bars.

2. A rail tie consisting of a metallic shell having parallel side walls and provided with a filler of concrete, longitudinal reinforcing bars arranged in parallel relation with the 10 side walls of the shell, transverse bottom braces connecting the side walls beneath the lower edges of said reinforcing bars, transverse rest bars disposed adjacent to the upper edge of the shell in the planes of the 15 rails supported by the tie, and clamping means for securing the rails in position consisting of adjustably connected jaws arranged between the planes of and pivotally mounted upon said longitudinal reinforcing bars.

3. A rail tie consisting of a metallic shell having parallel side walls and provided with a filler of concrete, longitudinal reinforcing bars arranged in parallel relation with the 25 side walls of the shell, transverse bottom braces connecting the side walls beneath the lower edges of said reinforcing bars, trans-

verse rest bars disposed adjacent to the upper edge of the shell in the planes of the rails supported by the tie, and clamping 30 means for securing the rails in position consisting of jaws having transverse fulcrum pins engaged with slots in said longitudinal reinforcing bars, and adjusting rods or bolts connecting said jaws.

4. A rail tie consisting of a metallic shell having parallel side walls and provided with a filler of concrete, longitudinal reinforcing bars arranged in parallel relation with the side walls of the shell, transverse bottom 40 braces connecting the side walls beneath the lower edges of said reinforcing bars, transverse rest bars disposed adjacent to the upper edge of the shell in the planes of the rails supported by the tie, and clamping 45 means for securing the rails in position consisting of jaws having transverse fulcrum pins engaged with slots in said longitudinal reinforcing bars, and adjusting rods or bolts connecting said jaws and extended between the planes of said rest bars and the 50 bases of the rails seated upon the tie.

In testimony whereof I affix my signature.
THOMAS D. WRIGHT.
